Primary Examiner — Jae Liang*Assistant Examiner* — Ji Sun Yoon(74) *Attorney, Agent, or Firm* — SLEMAN & LUND LLP(57) **CLAIM**

The ornamental design for a beverage holder, as shown and described.

DESCRIPTION

FIG. 1 is a front perspective view of a first embodiment of a beverage holder showing my new design;

FIG. 2 is a top plan view thereof;

FIG. 3 is a right side, left side, front and back view thereof, all of which are the same;

FIG. 4 is a bottom view thereof;

FIG. 5 is a front perspective view of a second embodiment of a beverage holder showing my new design;

FIG. 6 is a top plan view thereof;

FIG. 7 is a right side, left side, front and back view thereof, all of which are the same;

FIG. 8 is a bottom view thereof;

FIG. 9 is a front perspective view of a second embodiment of a beverage holder showing my new design;

FIG. 10 is a top plan view thereof;

FIG. 11 is a right side, left side, front and back view thereof, all of which are the same; and,

FIG. 12 is a bottom view thereof.

1 Claim, 3 Drawing Sheets(56)
